(57) **CLAIM**

The ornamental design for a lighter, as shown and described.

DESCRIPTION

FIG. 1 is a first perspective view of a lighter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is another perspective view of the lighter, shown in an alternate state of use.

The broken lines shown in the drawings depict portions of the lighter in which the design is embodied that form no part of the claimed design.
